UNITED STATES PATENT OFFICE.

GEORGE LEMAK, OF ALPHA, NEW JERSEY.

CHAIN-STRETCHING DEVICE.

963,052.

Specification of Letters Patent.

Patented July 5, 1910.

Application filed February 15, 1910. Serial No. 544,126.

To all whom it may concern:

Be it known that I, GEORGE LEMAK, a subject of Austria-Hungary, residing at Alpha, county of Warren, State of New Jersey, have invented a new and useful Chain-Stretching Device, of which the following is a specification.

My invention relates to a novel construction of a chain stretching device wherein I employ a bar having rack teeth thereon, said bar being longitudinally movable in a suitable body, portions of said bar and body being provided with lugs or projections adapted to engage a chain and provision being made for actuating said bar and causing the latter to travel longitudinally of the supporting body, and means being provided after stretching of the device has been effected, for permitting the bar to be drawn into its initial position.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of a chain stretching device embodying my invention. Fig. 2 represents, on an enlarged scale, a plan view of Fig. 1. Fig. 3 represents a section on line $y-y$, Fig. 2. Fig. 4 represents, on an enlarged scale, a side elevation showing the manner of supporting the mechanism for actuating the stretching bar. Fig. 5 represents a section on line $x-x$, Fig. 4.

Similar numerals of reference indicate corresponding parts in the figures.

Referring to the drawings: 1 designates the stretching bar which is provided at one extremity with the deflector, hook or lug 2 and has on its outer face, the ratchet teeth 3 which are adapted to be engaged by the nose 4 of the operating lever 5, which is ful-

crumed on the pin 6 which extends through the oppositely located arms 7 which are pivotally mounted at the point 8, upon the body portion 9 of the stretching device, the same comprising the side members or walls 10, at or near the lower extremity of which is formed the hook or lug 11 which is located so as to face the hook or lug 2 as will be understood from Fig. 1. The stretching bar 1 slides within the side walls 10 and is held in position therein by means of the bottom wall 12 and the top walls or cross-pieces 13 and 14, as will be understood from Fig. 3, the side walls or members 10 being properly braced or secured in assembled position by means of the transverse fastening devices 15.

At or near the extremity 16 of the pivotally mounted arms 7 is located the recess 17 which engages one end of the spring or tension device 18, the other end of the latter being located in the recess 19, whereby the arms 7, at all times, have such a tension exerted on them as will facilitate the operation of the actuating lever 5, one of said arms 7 having a pin 20 secured thereon, said pin being guided in a curved slot 21 of the lug 22 on the side member 10.

23 designates a pawl or tooth mounted on the locking member 24 which is pivoted at the point 8, said member 24 terminating in the resilient end 26 which bears on the pin 27 as will be understood from Fig. 3. One extremity of the member 24 is forked or bifurcated as indicated at 28 and has pivotally mounted thereon, the lever 29, the latter being provided with the cam face 30 which is adapted to seat upon or contact with the member 14 when said lever is turned from the position seen in full lines, Fig. 3, to the position seen in dotted lines in said figure, in which position the pawl or tooth 23 is moved out of engagement with the rack teeth 3 so that the stretching bar 1 can slide freely and unobstructedly in the body 9.

31 designates a thumb-screw mounted in the lug 32 which is adapted to be in engagement with the operating lever 5 when the same is in the position seen in Fig. 2, where-

by said lever is temporarily locked in inoperative position, as will be explained.

33 designates the link of the chain to be stretched which is in engagement with the lug 2, while 34 represents the oppositely located link of the chain which is in engagement with the lug 11, as will be understood from Fig. 1.

The operation is as follows:—The parts 10 normally appear as seen in Fig. 2, wherein the thumb-screw 31 is screwed tightly against the lever 5 so that the nose 4 is out of engagement with the rack teeth 3 and the stretching bar can be moved longitudinally 15 toward or away from the lugs 11 according to the distance between the links 33 and 34 of the chain to be stretched. The lug 2 of the stretching bar 1 and the lug 11 having been applied to the chain to be stretched in 20 substantially the manner indicated in Fig. 1, the set screw 31 is loosened and the actuating lever 5, rocked into its extreme positions, as will be understood from Figs. 1 and 3, whereupon the nose 4 will engage the rack 25 teeth 3 and will cause the lug 2 to move toward the lug 11. By reason of the pivotal mounting of the arms 7 on the pin 8 and the application of the tension device 18 thereto, the nose 4 of the lever 5 is permitted to 30 readily ride over the rack teeth 3 so that the stretching bar 1 progresses, it is held in its advanced position by the engagement of the 35 tooth or pawl 23 with the contiguous rack tooth as will be understood from Fig. 3, it being understood that the lever 29 is normally in the position seen in Figs. 1, 2 and 4, during the actuation of the stretching 40 bar 1.

After the chain has been stretched to the desired extent, the contiguous links can be brought together and united by a pin 35 as indicated in Fig. 1. The stretching bar 1 45 can then be restored to its initial position by turning the lever 29 from the position seen in full lines, Fig. 3, to the position seen in dotted lines in said figure, whereupon the pawl 23 is moved out of engagement with 50 the contiguous rack teeth and the actuating lever 5, having been turned into the position seen in Fig. 2 and locked therein, by the said screw 31, it will be apparent that the rack bar 1 will be free to slide in either direction 55 in the recess formed by the side members 10 and the members 12, 13 and 14.

In the construction shown, which I have found in practice to give satisfactory and reliable results, I employ the side members 60 25 which are suitably secured to the body 9, as will be understood from Figs. 1 and 2, the pin 8 preferably passing through the arms 7 and said side members 25 and serv-

ing as the fulcrum or pivot for said arms 7, as will be understood from Fig. 4, and 65 also for the locking member 24, as will be understood from Fig. 3. It will be understood that my invention is capable of being used for the stretching of chains of various sizes and dimensions and that the same is 70 also capable of being applied to stretch other materials than chains and I therefore do not wish to be restricted to any particular kind of material which is to be stretched, although in the present instance, I have 75 shown, as in Fig. 1 of the drawings, my invention especially adapted to the stretching of a chain.

In order to prevent the stretching bar 1 from falling from the body 9, I preferably 80 provide the same with a stop 36 which is adapted to contact with the extremity 37 of the strip 12 so that there is no liability of the stretching bar 1 falling from the body 9, as stated.

Having thus described my invention, what I claim as new and desire to secure by Letters Patent, is:—

1. In a stretching device, a body, a stretching bar slidable in said body, means on said body and bar for engaging the material to be stretched, rack teeth on said bar, an operating lever having an end adapted to engage said teeth, arms movably mounted on said body in which said operating lever is pivoted and a tension device for said arms.

2. In a stretching device, a body having a link-engaging lug, a stretching bar sliding in said body and provided with a link-engaging lug and with a series of rack-teeth, 100 arms movably mounted on the body, a lever fulcrumed in said arms and having one end engaging the rack teeth, and tension means connected to said arms to movably force them toward the bar.

3. In a stretching device, a body, a lug projecting therefrom, a stretching bar adapted to slide in said body, rack teeth on said bar, movable arms mounted on said body, a tension device for said arms, a guiding device for said arms, an operating lever mounted in said arms and having an end adapted to engage said teeth, a locking device for said rack, and means for rendering said locking device temporarily inoperative.

4. In a stretching device, a body, a lug projecting therefrom, a stretching bar adapted to slide in said body, rack teeth on said bar, movable arms mounted on said body, a tension device for said arms, a guiding device for said arms, an operating lever mounted in said arms and having an end adapted to engage said teeth, a locking device for said rack, a lever having a cam face pivotally mounted on said locking device and an abutment against which said

cam face is adapted to contact when said locking device is temporarily disengaged from said rack teeth.

5. In a stretching device, a body, a stretching bar slideable in said body, rack teeth on said bar, an operating lever having an end adapted to engage said teeth, arms movably mounted in which said lever is

pivoted, a tension device for said arms, and a set screw carried by said body and adapted to engage said operating lever and locking the same in inoperative position.

GEORGE LEMAK.
